UNITED STATES PATENT OFFICE.

JOSEPH M. DIDERO, OF CLEVELAND, OHIO.

DESIGN FOR AN ICE-CREAM SHOVEL.

51,586.

Specification for Design.

Patented Dec. 18, 1917.

Application filed August 30, 1917. Serial No. 189,036. Term of patent 14 years.

To all whom it may concern:

Be it known that I, JOSEPH M. DIDERO, a citizen of the United States, residing at Cleveland, in the county of Cuyahoga and State of Ohio, have invented a new, original, and ornamental Design for Ice-Cream Shovels, of which the following is a specification, reference being had to the accompanying drawings, forming part thereof.

Figure 1 is a front elevation of an ice cream shovel showing my new design.

Fig. 2 is a side elevation of the same; and

Fig. 3 is a sectional view on the line 3—3 of Fig. 1 indicating the shape of the blade and particularly the edge portion thereof which can be illustrated in no other way.

I claim:

The ornamental design for an ice cream shovel, as shown.

JOSEPH M. DIDERO.
